UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

REFRIGERATOR CAR

Application filed January 22, 1931. Serial No. 510,388.

This invention relates to refrigerator cars, and particularly to refrigerator cars having metal roofs. It has for its principal objects to provide an efficient and compact arrangement of the roof insulation, which for a given headroom will decrease the over-all height of the car or for a given over-all height will increase the headroom thereof; to provide for holding the insulation in place, to provide a simple arrangement for supporting the members that frame the hatch openings in the metal roof and for supporting said roof adjacent to said openings; and to provide for ease of assembly, cheapness of construction and economy of design. The invention consists principally in the combinations and arrangements of parts herein-after described and claimed.

In the accompanying drawings, which form part of this specification and wherein like symbols refer to like parts wherever they occur,

Fig. 1 is a plan view of a portion of refrigerator car embodying my invention,

Fig. 2 is an enlarged vertical transverse section through one-half of the upper portion of the car on the line 2-2 of Fig. 1.

Fig. 3 is a vertical transverse section through the eaves portion of the car on the line 3-3 in Fig. 1,

Fig. 4 is a vertical longitudinal section at the ridge of the car on the line 4-4 in Fig. 1,

Fig. 5 is a vertical transverse section through the car at one of the hatch openings, the section being taken on the line 5-5 of Fig. 1; and

Fig. 6 is a vertical longitudinal section through the car at said hatch opening on the line 6-6 in Fig. 1.

Referring to the accompanying drawings, my invention is shown in connection with a refrigerator car having a body frame comprising wooden side plates 1 that are connected by metal carlines 2 preferably in the form of Z-bars arranged with their webs vertical. The wooden side plates 1 are preferably reinforced along their inner lower corners by means of metal members in the form of Z-bars 3 that are arranged with their webs ver-

tical and bearing against the inner faces of said side plates and with their lower flanges extending outwardly beneath the side plates and with their upper flanges extending inwardly. The Z-bar reinforcing members 3 are rigidly secured to the side plates 1 preferably by means of bolts 3a.

The refrigerator car is provided with a single course metal roof construction which preferably comprises metal load sustaining sheets 4 that slope downwardly from ridge to eaves of the car and have upstanding flanges 5 along their adjacent side margins that are enclosed in inverted U-shaped seam caps 6 that have outstanding base flanges 7 that overlie the adjacent side marginal portions of the roof sheets. The seam caps 6 are rigidly secured to the upstanding seam flanges 5 of adjacent roof sheets by rivets 8 that extend horizontally through said seam caps and said seam flanges. Each eaves end of the roof sheets and seam caps is bent downwardly and the adjacent end portions of the sheets are rigidly secured by rivets 9 to the sloping top flange of an eaves angle strip 10 whose vertical flange is secured to the outer face of the side plate by means of horizontal bolts 11. The lower portion of the eaves angle 10 is offset outwardly so as to cap the upper ends of the side sheathing 12 of the car, thereby preventing water and snow from reaching the interior of the car between the side plates and the side sheathing. Side fascia boards 13 are secured to the side plates between the outer surfaces of the side sheathing 12 and the depending eaves flanges of the roof sheets. The side fascia boards extend above the lower edges of the eaves flanges of the roof sheets and below the lower edges of the metal sheet supporting angles 10 and thus serve to protect said angles and the securing bolts 11 therefor from the weather.

The Z-shaped carlines 2 of the car body are preferably located below the tops of the side plates to which they are rigidly secured preferably by means of end fittings or brackets 14 that are riveted to the webs of said carlines and have a laterally extending end flange that fits flatwise against the web of the adjacent Z-bar side plate reinforcing 100

member 3. Preferably the body or sub-carlines 2 are offset with relation to the vertical planes of the roof seams, which function after the manner of exterior or outside carlines. The base flanges 2a of the Z-shaped subcarlines 2 extend horizontally from side plate to side plate; but the webs of said carlines gradually decrease in depth from the middle towards the ends thereof with the result that the top flanges 2b of said carlines slope downwardly on opposite sides of the ridge line of the car. Each carline is reinforced and stiffened by means of wooden filler members 15 and 16 that are secured to the opposite sides of the web of the carline by bolts 17 and extend longitudinally of the carline substantially from end to end thereof. The filler member 15 has its upper surface inclined to fit the underside of the sloping top flange 2b of the carline and has a horizontally extending bottom to which a ceiling 18, preferably of tongue-and-groove boards is nailed or otherwise rigidly secured. The carline filler 16 rests upon the horizontal base flange 2a of the carline with its upper edge spaced thereabove and sloping downwardly from the middle of the carline to the ends thereof in conformity with the pitch or slope of the metal roof located thereabove.

Supported on top of the carline fillers 16 is a layer of relatively rigid insulating material 19, such for instance as the material known in the trade as "Celotex", which extends in a continuous layer across said carline fillers from side plate to side plate. The space between this relatively rigid lower layer of insulating material 19 and the metal roof is filled with layers of relatively flexible insulating material 20, such for instance as material of the kind known in the trade as "Dry Zero". This relatively flexible insulating material 20 extends continuously from side plate to side plate and across the tops of the carlines and is held in place at the sides of the car by means of wooden cleats 21 that are pressed down upon the edges of such material and are nailed in this position to the inner side faces of said plates. The portion of the relatively flexible insulating material 20 located intermediate the cleats 21 is held in place by means of the metal roof which serves to compress the material slightly between the underside of said roof and the relatively rigid lower layer of insulation 19.

Located beneath the metal roof intermediate the two seams at each end of the car are two wooden carlines 22 that extend from side plate to said plate and are spaced apart longitudinally of the car. The wooden carlines 22 have their lower edges disposed horizontally at the level of the lower edges of the combined reinforcing and nailing strips 15 of the Z-shaped carlines 2 and thus serve as nailing strips for the ceiling 18; and the upper edges of these wooden carlines slope downwardly on opposite sides of the ridge and serve as supports for the roof sheet located thereabove. The innermost carline of these two wooden carlines has a nailing strip 23 secured to the side thereof that faces the middle of the car, which strip serves to support the adjacent end of the relatively rigid lower layer of insulation 19; and the adjacent end of the flexible insulation 20 is held in position by wooden cleats 24 that are pressed down upon the edges of such material and are nailed in this position to said side of said wooden carline. The insulation in the space between the endmost wooden carline 22 and the end plate 25 of the car preferably extends horizontally from side plate to side plate and is preferably held down upon the ceiling 18 by means of wooden cleats 26 that are nailed to the opposing faces of said carline and said end plate.

The two wooden carlines are connected on each side of the ridge by two wooden cross-members 27 that cooperate with said carlines to form a frame adapted to receive and support a hatch frame 28, which is nailed to said carlines and said cross-members and extends upwardly through an opening provided therefor in the metal roof, the edges of such opening being flanged up around said hatch frame. By this arrangement, the two end carlines 22, together with the cross-members 27, serve not only to support the hatch frame 28, but they also serve to support the metal roof where it is cut out to accommodate said hatch frame.

By the arrangement described, the insulation is disposed entirely above the sub-carlines and is held in place between the side plates by the metal roof. It is noted that said insulation slopes downwardly from the ridge to the eaves in a plane parallel to the slope of the roof and the sloping top surfaces of the insulating supporting strips of the carlines, thereby overcoming the tendency for the insulation to shift crosswise of the car. It is also noted by thus arranging the insulation above the carlines the outside height of the car may be reduced without decreasing the headroom thereof or the headroom of the car may be increased without increasing the outside height thereof. It is further noted that the portions of the body frame below the main insulation are protected by the wooden ceiling boards so that there is no metal exposed in the interior of the frame. It is also noted that the two end carlines and their cross-connections constitute supports for the hatch frames and the portions of the metal roof that surround said frame. It is also noted that the construction embodies in the refrigerator car the advantages of a metal car roof whose seams function as outside carlines and thus cooperate with the carlines of the car body to increase the strength and rigidity thereof.

What I claim is:

1. A refrigerator car comprising side plates, carlines connecting said side plates, a single course metal roof extending from 5 side plate to side plate above said carlines, and insulation substantially filling the space between the tops of said carlines and the underside of said single course metal roof.
2. A refrigerator car comprising side 10 plates, carlines connecting said side plates, a single course metal roof supported by said side plates independently of said carlines, and insulation substantially filling the space between the tops of said carlines and the underside of said single course metal roof.
3. A refrigerator car comprising side 15 plates, carlines connecting said side plates, a single course metal roof supported by said side plates independently of said carlines, and insulation located between the tops of 20 said carlines and the underside of said single course metal roof, said insulation comprising a layer of relatively rigid insulation supported on top of said carlines and a plurality of layers of relatively flexible insulation held by and between said layer of relatively rigid insulation and said roof.
4. A refrigerator car comprising side 25 plates, carlines connecting said side plates, a single course metal roof supported by said side plates above and independently of said carlines, and insulation supported on said carlines and filling the space between the latter and said single course metal roof.
5. A refrigerator car comprising side 30 plates, carlines connecting said side plates, a single course metal roof supported by said side plates above and independently of said carlines, insulation supported on said carlines and filling the space between the latter and said single course metal roof.
6. A refrigerator car comprising side 35 plates, carlines connecting said side plates, a roof supported by said side plates above and independently of said carlines, and insulation substantially filling the space between the tops of said carlines and the underside of said roof.
7. A refrigerator car comprising side 40 plates, carlines connecting said side plates, a roof supported by said side plates above and independently of said carlines, insulation located between the tops of said carlines and the underside of said roof and substantially in contact with said roof, and a ceiling secured to the undersides of said carlines.
8. A refrigerator car comprising side 45 plates, carlines connecting said side plates, a pitched or arched single course metal roof supported by said side plates and spaced above said carlines, and insulation located in the space between said carlines and roof, said insulation being clamped by and between said roof and said carlines and sloping down- 50 wardly on opposite sides of the ridge in conformity with the pitch of said roof.
9. A refrigerator car comprising side 55 plates, carlines connecting said side plates, a self-sustaining pitched or arched roof supported by said side plates and spaced above 60 said carlines, and insulation located between the tops of said carlines and the underside of said roof, said insulation being clamped by and between said roof and said carlines and sloping downwardly on opposite sides of the 65 ridge in conformity with the slope of said roof.
10. A refrigerator car comprising side 70 plates, carlines extending from side plate to side plate, a pitched single course metal roof supported by said side plates above said carlines, the upper surfaces of said carlines sloping downwardly on opposite sides of the 75 ridge in conformity with the pitch of the roof, and layers of insulation located between the undersurface of said roof and the upper surface of said carlines.
11. A refrigerator car comprising side 80 plates, carlines extending from side plate to side plate, a pitched single course metal roof supported by said side plates above said carlines, each of said carlines comprising a Z-member arranged with its web vertical, a wooden filler strip secured to the web of said 85 Z-bar beneath the top flange thereof, a ceiling secured to said strip, a wooden strip supported on the bottom flange of said Z-bar and having its upper surface spaced below said roof and conforming to the pitch thereof, and insulation located between and substantially in contact, the undersurface of said metal roof and the upper surface of said last 90 mentioned strip of each carline.
12. A refrigerator car comprising side 95 plates, carlines extending from side plate to side plate, a pitched single course metal roof supported by said side plates above said carlines, each of said carlines comprising a Z-member arranged with its web vertical, its lower flange horizontal and its upper flange sloping downwardly on opposite sides of the 100 ridge, a wooden filler strip secured to the web of said Z-bar beneath the top flange thereof, a ceiling secured to said strip, a wooden strip supported on the bottom flange of said 105 Z-bar and extending above the top flange of said carline and having its upper surface spaced below said roof and conforming to the pitch thereof, and layers of insulation located between the undersurface of said metal roof and the upper surface of said last mentioned strip of each carline.
13. A refrigerator car comprising side 110 plates, carlines extending from side plate to side plate, a pitched single course metal roof supported by said side plates above said carlines, each of said carlines comprising a Z-member arranged with its web vertical, its lower flange horizontal and its upper 115 flange sloping downwardly on opposite sides of the ridge, a wooden filler strip secured to the web of said Z-bar beneath the top flange thereof, a ceiling secured to said strip, a wooden strip supported on the bottom flange of said Z-bar and extending above the top flange of said carline and having its upper surface spaced below said roof and conforming to the pitch thereof, and layers of insulation located between the undersurface of said metal roof and the upper surface of said last 120 mentioned strip of each carline.
14. A refrigerator car comprising side 125 plates, carlines extending from side plate to side plate, a pitched single course metal roof supported by said side plates above said carlines, each of said carlines comprising a Z-member arranged with its web vertical, its lower flange horizontal and its upper 130 flange sloping downwardly on opposite sides of the ridge, a wooden filler strip secured to the web of said Z-bar beneath the top flange thereof, a ceiling secured to said strip, a wooden strip supported on the bottom flange of said Z-bar and extending above the top flange of said carline and having its upper surface spaced below said roof and conforming to the pitch thereof, and layers of insulation located between the undersurface of said metal roof and the upper surface of said last mentioned strip of each carline.

per flange sloping downwardly on opposite sides of the ridge in conformity with the slope of the roof, wooden filler strips secured to the webs of said carlines beneath the top flanges thereof, a ceiling secured to said strips, wooden filler strips supported on the bottom flanges of said carlines and having their upper surface spaced below said roof and conforming to the pitch thereof, and insulation located between the undersurface of said roof and the upper surface of said last mentioned filler strips, said insulation comprising a layer of relatively rigid insulation supported on said last mentioned filler strips and layers of relatively flexible insulation compressed by and between said relatively rigid insulation and said roof.

14. A refrigerator car comprising side plates, carlines connecting said side plates, a single course metal roof extending from side plate to side plate and spaced above said carlines, insulation substantially filling the space between the tops of said carlines and the underside of said roof, and cleats secured to the inner surfaces of said side plates and binding the edges of said insulation.

15. A refrigerator car comprising side plates, carlines connecting said side plates, cross-members extending from carline to carline, said carlines and cross-members cooperating with each other to form a frame, and a hatch frame enclosed and supported in the frame formed by said carlines and said cross-members.

16. A refrigerator car comprising side plates, carlines connecting said side plates, cross-members extending from carline to carline, a hatch frame secured in the opening defined by said carlines and said cross-members, said hatch frame comprising frame members secured to said cross-members and frame members secured to said carlines, and a metal roof supported on said side plates, said metal roof being provided with an opening adapted to accommodate said hatch frame, the portions of the metal roof adjacent to said opening being supported on the tops of said carlines and said cross-members.

Signed at New Kensington, Pennsylvania,
this 19th day of January, 1931.

CHARLES DAVID BONSALL.
